SERVING TRAY

George Filipowski, 445 E. 65th St., New York, N.Y.

Filed Aug. 20, 1963, Ser. No. 76,287

Term of patent 14 years

(Cl. D44—10)

FIG. 1 is a top plan view of a serving tray showing my new design;

FIG. 2 is a side elevational view thereof;

FIG. 3 is a bottom plan view thereof.

I claim:

The ornamental design for a serving tray, as shown.
